Primary Examiner — Derrick E Holland*Assistant Examiner* — Andrew Kerr(74) *Attorney, Agent, or Firm* — Kilpatrick Townsend and Stockton LLP(57) **CLAIM**

We claim the ornamental design for a coffee dripper, substantially as shown and described.

DESCRIPTION

FIG. 1 is a top perspective view of a coffee dripper, showing our new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines in the drawings depict portions of the coffee dripper that form no part of the claimed design.
